CLOSURE FOR CONTAINERS

Houstan L. Willis, Gloucester, Ohio

Application June 19, 1933, Serial No. 676,425

6 Claims. (Cl. 215—38)

More particularly this invention relates to a closure for a milk bottle, the general object of the invention being to provide a new and improved closure which is simple in construction and which may be effectively secured to the bottle.

Another object is to provide a closure comprising a circular paper cover which may be positioned on top of the bottle and is recessed so as to extend down against the cap seat, together with a disk cap which may be applied by the machines which are ordinarily used for applying a disk cap alone.

Another object is to provide a closure comprising a paper cover together with a disk cap, the cover being so formed that when the cap is pressed into place the edge of the cap expands portions of the cover into effective locking engagement with the side walls of the recess forming the cap seat.

Further objects will become readily apparent from the following detailed description taken in connection with the accompanying drawing, in which:

Fig. 1 is a plan view of a preferred form of the invention.

Fig. 2 is a fragmentary vertical central section through the upper portion of a milk bottle showing a paper cover in place and a disk cap partially inserted.

Fig. 3 is a similar view showing the disk cap in its seated position.

Fig. 4 is a fragmentary section similar to Fig. 2, showing a modified form of the invention.

While I have shown in the drawing and shall herein describe in detail a preferred embodiment of the invention, together with a modification thereof, it is to be understood that I do not thereby intend to limit the invention to the specific forms disclosed, but aim to cover all modifications and alternative constructions falling within the spirit and scope of the invention as expressed in the appended claims.

In the drawing the invention is illustrated as applied to a milk bottle having a neck 5 provided with an annular lip 6 and an annular recess 7 forming a cap seat 8. The wall 9 of the recess is generally inclined as shown so that when an ordinary disk cap is applied to the bottle it is forced past the mouth 10 in a somewhat contracted state so as afterwards to expand into the recess 7. As shown in Figs. 1 to 3 the invention in its preferred form comprises a paper cover 12 and a disk-like cap 13 of heavier and stiffer material. The cover 12 has a central disk-like por-

tion 12' adapted to engage against the annular seat 8, and an annular rim portion 12'' extending upwardly from the disk portion and over the lip of the bottle and, preferably, downwardly partially around the lip of the bottle so as to provide a protective covering. The rim portion is formed integrally with the disk portion and has a pleat 14 formed by reverse folds 14' and 14'' so as to provide a plurality of thicknesses of paper surrounding the edge of the cap 13 when in its seated position as illustrated in Fig. 3. The cap is preferably formed of a diameter such that it will contract sufficiently to permit the cap to be pressed through the rim portion of the cover, past the mouth 10 of the bottle, and down into engagement with the disk portion 12', the pleat 14 of the cover then being expanded from the position shown in Fig. 2 to the position shown in Fig. 3, so that the pleat is forced into the recess 7.

With a cap of a diameter which will just pass a single thickness of the paper cover at the mouth 10, an effective locking of the closure to the bottle is secured. If an attempt is made to remove the closure without first removing the cap, the several thicknesses of paper surrounding the edge of the cap enlarge this portion of the closure so that it will not pass upwardly through the mouth of the bottle. In this way the annular pleat constitutes a locking means formed on and carried by the cover, which means is contracted during the application of the paper cover to the bottle and is then expanded by the disk cap so as to interlock with the recess 7 and the inclined wall 9 thereof. Furthermore by providing the pleat in the paper cover it is possible to compensate for the variations existing in different bottles in the distance between the shoulder 8 and the top of the lip so that the disk portion 12' may always be pressed into engagement with the seat 8, without drawing the rim portion of the cover over the lip of the bottle and pulling the outer portion of the rim out of contact with the bottle surface.

In the form illustrated in Fig. 4 the cover is creased at 16, 17 and 18 so that the pleat, prior to the insertion of the cap, extends as a bead horizontally into the neck of the bottle. In either case, three thicknesses of paper surround the cap 13 when in its seated position.

The invention provides a closure embodying a disk cap which may be applied by ordinary capping machines. The paper covers may first be placed loosely upon bottles filled with milk prior to their passage to the capping machine, after which the disk caps may be automatically applied

in the usual manner. The construction thereby avoids the necessity of any special machine for this purpose, it being merely necessary to provide disk caps slightly smaller in diameter than those which would ordinarily be used if no paper cover were applied.

I claim as my invention:

1. A closure for a milk bottle having an annular recess formed inside the lip of the bottle to provide a cap seat, comprising, in combination, a paper cover having a depressed central portion fitting into the mouth of the bottle and against said seat, and an annular rim portion extending upwardly from the central portion and over the lip of the bottle, said rim portion having a plurality of creases circumscribing the central portion forming a pleat adjacent said seat, and a disk cap adapted to be forced past the rim portion of the cover and into engagement with the central portion thereof so as to force the pleat into said recess and lock the closure to the bottle.
2. A closure for a milk bottle having an annular recess formed inside the lip of the bottle to provide a cap seat and an inclined wall adjacent said seat, comprising, in combination, a paper cover having a central depressed disk portion fitting into the mouth of the bottle and against said seat, and an annular rim portion extending upwardly from the disk portion and over and partly around the lip of the bottle, said rim portion having a plurality of creases forming an annular pleat adjacent the disk portion, and a disk cap adapted to be forced through the opening formed by the lip of the bottle and past the rim portion of the cover and into engagement with the disk portion thereof so as to expand the pleat into said recess and lock the closure to the bottle.
3. A closure for a milk bottle having an annular recess formed inside the lip of the bottle to provide an annular cap seat, comprising, in combination, a paper cover having a depressed central disk portion fitting into the mouth of the bottle and against said seat and an annular rim portion extending upwardly from said central portion and over the lip of the bottle so as to form a protective covering therefor, a disk cap adapted to be forced past the rim portion of the cover and into engagement with the seated portion thereof, and a preformed annular fold on said cover adapted to be expanded by said disk cap into interlocking engagement with the recess so as to prevent removal of the closure without first removing the cap.

ment with the central portion thereof, and an annular preformed bead on said cover adjacent said disk portion adapted to be expanded by said disk cap into interlocking engagement with the recess so as to prevent removal of the closure 5 without first removing the cap.

4. A closure for a bottle having an annular recess formed inside the lip of the bottle to provide a cap seat, comprising, in combination, an annular paper member overlying the lip of the bottle 10 and extending downwardly into said recess to a position adjacent said seat, and a disk cap adapted to be forced through the opening formed by the lip of the bottle and into said recess, said paper member having an annular doubled over 15 portion adjacent said seat adapted to be expanded into said recess by said disk cap to lock the closure to the bottle.

5. A closure for a milk bottle having an annular recess formed inside the lip of the bottle to provide a cap seat, comprising, in combination, an annular paper member overlying the lip of the bottle and extending downwardly into said recess to a position adjacent said seat, and a disk cap adapted to be forced through the opening formed 20 by the lip of the bottle and into said recess, said paper member having an annular pleat adjacent said seat adapted to be expanded into interlocking engagement with said recess by said disk cap.

6. A closure for a container having an annular recess formed inside the lip of the container to provide a cap seat comprising, in combination, a paper cover having a depressed central portion fitting into the mouth of the container and against said seat and an annular rim portion 35 extending upwardly from said central portion and over the lip of the container so as to form a protective covering therefor, a disk cap adapted to be forced past the rim portion of the cover and into engagement with the seated portion thereof, and a preformed annular fold on said cover adapted to be expanded by said disk cap into interlocking engagement with the recess so as to prevent removal of the closure without first removing the cap. 45

HOUSTIN L. WILLIS.
